UNITED STATES PATENT OFFICE.

ROBERT D. CLARK, OF DUQUESNE, PENNSYLVANIA.

SAFETY ELEVATOR DEVICE.

1,015,137.

Specification of Letters Patent.

Patented Jan. 16, 1912.

Application filed March 24, 1911. Serial No. 616,670.

To all whom it may concern:

Be it known that I, ROBERT D. CLARK, a citizen of the United States of America, residing at 219 Peter street, Duquesne, in the 5 county of Allegheny and State of Pennsylvania, have invented certain new and useful Improvements in Safety Elevator Devices, of which the following is a specification, reference being had therein to the accompanying drawing.

This invention relates to safety elevator devices, and the objects of my invention are, first, to furnish an elevator cage with positive and reliable means to prevent a sudden 15 descent of the same should the hoisting cables thereof break; second, to provide a safety device for elevators that is automatic in its action and free from injury by ordinary use, and third, to accomplish the above 20 results by a mechanical construction that is simple, easy to install and highly efficient for the purposes for which it is intended.

With the above and other objects in view the invention resides in a novel construction, combination and arrangement of parts 25 to be hereinafter specifically described and then claimed.

Reference will now be had to the drawing, wherein like numerals of reference designate 30 corresponding parts throughout the several views, in which:—

Figure 1 is a side elevation of the safety device as applied to an elevator cage, showing it in an inactive position. Fig. 2 is a 35 similar view showing the device in an active position. Fig. 3 is a horizontal sectional view taken on the line III—III of Fig. 1. Fig. 4 is a similar view taken on the line IV—IV of Fig. 2, and Figs. 5 and 6 are detail views of modified forms of gripping 40 wheels.

The reference numerals 1 denote the vertical frames of an elevator shaft or well and secured to the confronting sides of these 45 frames are vertical T rails 2. Movable between the rails 2 is an elevator cage, comprising a transverse top beam 3, a bottom beam 4 and vertical channel bars 5 connecting said beams, said beams and bars constituting the main frame work of a conventional 50 form of elevator cage.

The beam 3 has the side walls thereof, intermediate the ends connected by a web 6 and movably mounted in said web is the 55 pending reduced end 7 of a yoke 8, said yoke

having the upper end thereof provided with an apertured lug 9 to which is connected one end of a hoisting cable 10. The lower end of the yoke is provided with a cup shaped washer 11 and a nut 12 or other holdfast device, and encircling the reduced end 7 of the yoke 8, between the cup shaped washer 11 and the web 6 is a coiled compression spring 13. The hoisting cable 10 is adapted to extend over hoisting drums not shown 60 and under a revoluble sheave 14, revolvably mounted upon a transverse bolt 15, carried by the yoke 8.

Loosely engaging the transverse bolt 15 are the longitudinally slotted arms 16 of 70 levers 17, said arms being mounted upon the bolt 15 between the sheave 14 and the yoke 8. The levers 17 are pivotally mounted upon transverse pins 18 mounted in the beam 3 adjacent to the ends thereof, and the lower ends of said levers are enlarged, as at 19 and bifurcated, as at 20 to accommodate eccentrically mounted gripping wheels 21 having the peripheries thereof toothed or roughened, as at 22, for a purpose that 75 will presently appear.

The enlarged lower ends of the levers 17 have apertured lugs 23 and pivotally connected to said lugs by pins 24 are sectional vertical rods 25 having the sections thereof 80 adjustably connected together, as at 26 somewhat similar to a turn-buckle. The rods 25 extend through tubes or housings 27 arranged between the beams 3 and 4, and the lower ends of said rods are loosely connected, as at 28 to the upper ends of levers 29 pivotally mounted upon transverse pins 30, carried by the beam 4. The outer ends of the levers 29 are provided with eccentrically mounted gripping wheels 31 similar 95 to the wheels 21.

In Fig. 5 there is illustrated a modified form of gripping wheel which is indicated at 21^a and is provided with a V-shaped groove. In Fig. 6 another modified form of gripping wheel is illustrated and which is indicated by the reference character 21^b and which gradually decreases in diameter from its center toward each end. The rails 2^a and 2^b respectively, Figs. 5 and 6, are of a 100 shape so as to be engaged by the wheels 21^a and 21^b respectively.

The gripping wheels are normally maintained in an inactive position, but are supported, during the operation of the elevator 110

cage, in proximity to the rails, whereby a very slight movement of said gripping wheels will immediately place the wheels in position to serve the purpose for which 5 they are intended.

When the hoisting cable 10 breaks, the upper ends of the levers 17, which are slotted and loosely mounted upon the bolt 15, will be released and lowered through the medium of the compression spring 13. In consequence of such release, the outer ends of the levers 17 and 29 will be elevated, carrying the wheels 21 and 31 into engagement with the guide rails 2. The sudden release 10 of the elevator cage tends to throw or revolve the gripping wheels 21 and 31, whereby they will frictionally engage the rails 2 and be in position to wedge and positively hold the cage relatively to the rails 2 after 15 it has been released.

The frame work of the elevator cage is of a conventional form and the safety device herein illustrated and described can be embodied in any form of elevator cage by providing the tubes or housings 27 that prevent 25 passengers or the operator of the cage from interfering with the automatic operation of the device when the hoisting cable breaks.

The invention is susceptible to such 30 changes as fall within the scope of the appended claims.

What I claim is:—

1. A safety device for elevators comprising the combination with guide rails, a vertically movable cage arranged between said rails, a hoisting cable for the cage, and a web carried by the cage, of a yoke having the reduced lower end extending through said web, a washer supported upon the 35 lower terminus of said reduced end, a spring surrounding the reduced end of said yoke and interposed between the web and said washer, a bolt carried by the enlarged portion of said yoke, a sheave on said bolt, said 40 hoisting cable connected by one end to said yoke and extending around said sheave, levers having their inner and outer ends provided with forks, the arms of the forks at the inner ends of the levers being 45 provided with elongated slots through which extends said bolt, means for pivotally connecting the forked outer ends with said cage, and gripping wheels mounted in the forked outer ends of said levers and adapted to engage 50 said rails.

2. A safety device for elevators comprising the combination with guide rails, a vertically movable cage arranged between said rails, a hoisting cable for the cage, and a web carried by the cage, of a yoke having the reduced lower end extending through said web, a washer supported upon the lower terminus of said reduced end, a spring 55 surrounding the reduced end of said yoke and interposed between the web and said

washer, a bolt carried by the enlarged portion of said yoke, a sheave on said bolt, said hoisting cable connected by one end to said yoke and extending around said sheave, levers having their inner and outer ends 70 provided with forks, the arms of the forks at the inner ends of the levers being provided with elongated slots through which extends said bolt, means for pivotally connecting the forked outer ends with said cage, gripping wheels mounted in the forked outer ends of said levers and adapted to engage said rails, vertically disposed adjustable rods pivoted at their upper ends to the outer forked ends of said levers and 75 extending through said cage, levers pivotally connected with the cage and having their inner ends pivotally connected to the inner ends of said rods and having their outer ends forked, and gripping wheels 80 mounted in the forked ends of the last mentioned levers and adapted to engage said rails.

3. A safety elevator device comprising the combination with guide rails, a vertically movable cage traveling between said rails, and a hoisting cable for the cage, of a web supported by the cage, a vertically disposed yoke extending through said web and carrying a washer, a spring surrounding the reduced end and interposed between the web and the washer, a bolt extending through said yoke above said web, a sheave pivotally mounted upon said bolt, said hoisting cable connected to the upper end of said yoke and 90 extending around said sheave, levers pivoted near their outer ends with said cage and having their inner ends provided with forks extending into said yoke, the arms of said forks provided with elongated slots through 95 which extends said bolt, and gripping elements carried by the outer ends of said levers and adapted to engage said rails.

4. A safety elevator device comprising the combination with guide rails, a vertically movable cage traveling between said rails, and a hoisting cable for the cage, of a web supported by the cage, a vertically disposed yoke extending through said web and carrying a washer, a spring surrounding the reduced end and interposed between the web and the washer, a bolt extending through said yoke above said web, a sheave pivotally mounted upon said bolt, said hoisting cable connected to the upper end of said yoke and 100 extending around said sheave, levers pivoted near their outer ends with said cage and having their inner ends provided with forks extending into said yoke, the arms of said forks provided with elongated slots 105 through which extends said bolt, gripping elements carried by the outer ends of said levers and adapted to engage said rails, levers pivotally connected with the lower end of said cage, gripping elements carried by 110

115 said cage, and gripping elements carried by the outer ends of said cage and adapted to engage said rails.

the last mentioned levers and adapted to engage said rails, and vertically disposed bars pivotally connected at their lower ends to the inner ends of the last mentioned elements and having their upper ends pivotally connected to the first mentioned levers in proximity to the outer ends thereof.

In testimony whereof I affix my signature in the presence of two witnesses.

ROBERT D. CLARK.
